PROCESS OF RECOVERING CASING-HEAD GASOLINE

Arthur John Lindsay Hutchinson, Palo Alto, Calif., assignor to The Fluor Corporation, Limited, Los Angeles, Calif., a corporation of California

Application November 2, 1936, Serial No. 108,721

8 Claims. (Cl. 196—8)

This invention relates to improvements in recovering gasoline from natural gas and has for its principal object the treatment of natural gas in such fashion that the same is substantially 5 completely denuded of desired constituents and a finished liquid gasoline product is obtained of such specifications as to be readily usable in industry.

Another object is to provide a process in which 10 initial construction costs for suitable apparatus can be immensely reduced over known processes achieving a similar result due to the fact that such apparatus can be greatly reduced in size owing to the efficiency of the process.

15 A further object is to provide a process of such efficiency that the operating costs of suitable apparatus are greatly reduced over those of operating known apparatus having the same capacity.

20 A further object is to provide a process in which heat losses are so minimized that, in continuous operation, by the use of efficient heat exchange fuel economy is a maximum.

Further objects and results will become apparent as the process hereinafter becomes more fully disclosed.

Natural gas as it comes from wells is a mixture of gaseous and vaporized hydrocarbons, certain of the latter being desired constituents of 30 so-called casing-head gasoline and are recovered in liquid form.

The series of hydrocarbons in natural gas consists generally of the methane series of hydrocarbons which, for the purpose of illustration 35 herein, may be indexed as follows:

Methane	C ₁
Ethane	C ₂
Propane	C ₃
Iso-butane	C ₄
Normal butane	C ₄
Iso-pentane	C ₅
Normal pentane	C ₅

45 Other hydrocarbons heavier than pentane occur but, for the purpose of this invention, the treatment of a mixture of the above hydrocarbons in gaseous form will be considered.

50 As is well known, the above series of hydrocarbons vary in boiling range from methane, the lowest, up to pentane, methane and ethane being normally in fixed gaseous condition at ordinary atmospheric temperatures.

It is an object of this invention to selectively 55 segregate constituents of the above mixture to

recover therefrom a finished casing-head gasoline with maximum economy.

More specifically, the process of this invention provides a casing-head gasoline having a relatively high percentage of the heavier hydrocarbons of the mixture, such as normal butane and heavier, when compared with the original natural gas in which the hydrocarbons lighter than normal butane predominate.

Further, the process of this invention provides 10 a casing-head gasoline which contains no methane, ethane, or propane, and a relatively small percentage of iso-butane.

Referring to the diagrammatic sheet of drawings which illustrates an operating process, natural gas is introduced through pipe 10 into an absorption tower, or absorber, 11 of any well-known type wherein selective absorption of desired constituents of the gas takes place.

Considering the process as operating continuously, the natural gas flow was at the rate of 65,000,000 cubic feet per twenty-four hours and had the following composition and percentages:

	Mol. %	25
C ₁	85.60	
C ₂	9.44	
C ₃	3.70	
C ₄	0.29	
C ₄	0.44	30
C ₅₊	0.53	

The abbreviation C₅₊ means iso-pentane, normal pentane, and any heavier constituents that may be present in the gas.

The gas flowing upwardly through tower 11 35 meets a downward flow of absorption oil of about 39.6 A. P. I. gravity supplied at the rate of about 254 gallons per minute, the same being chilled to a temperature of about 75° F.

The pressure in tower 11 is preferably about 40 425 pounds per square inch gage, for the run illustrated, but it should be understood that the process is flexible and pressures and temperatures may be varied with either increase or decrease to any desired amount depending on atmospheric 45 and operating requirement at the plant location.

Gas pipe lines are operated at pressures varying from about 100# to 800# per square inch and where cooling from 90° F. to 45° F. may be obtained. This present process can be advantageously used under all these conditions. It is understood that the oil rates must be correctly chosen for the operating pressures and temperatures in accordance with well known methods.

From the top of tower 11, undesired constitu-

ents generally termed "wild gases" pass out through pipe 12 controlled by back pressure regulator 13 at a temperature of about 75° F. and comprise 64,500,000 cubic feet of gas as follows:

	Mol. %
C ₁	86.25
C ₂	9.52
C ₃	3.73
10 C ₄	0.23
C ₄	0.27

The absorption oil containing the bulk of the desired constituents together with some undesired constituents passes out of the bottom of tower 11, controlled by liquid level regulator 14, at temperature of about 90° F. through pipe 15 to a vent tank 16 and comprises the following mixture and percentages:

	Mol. %
20 C ₁	12.22
C ₂	6.28
C ₃	7.40
C ₄	1.32
C ₄	2.44
25 C ₅₊	5.54
Absorption oil	64.80

Liquid level regulator 14 acts as a pressure regulator on pipe 15 to reduce the pressure in vent tank 16 to about 225 pounds per square inch whereupon certain gaseous and vaporous constituents pass off through pipe 17, controlled by back pressure regulator 18, to a stripper 19. These fractions are as follows:

	Mol. %
35 C ₁	80.40
C ₂	12.09
C ₃	6.15
C ₄	0.42
C ₄	0.64
40 C ₅₊	0.32

and together comprise 358,000 cubic feet.

Liquid hydrocarbons of a gravity of about 45° A. P. I. composed of the following:

	Mol. %
45 C ₁	8.04
C ₂	5.94
C ₃	7.47
C ₄	1.38
50 C ₄	2.45
C ₅₊	5.86
Absorption oil	68.90

at a temperature of about 85° F. and at the rate of about 275 gallons per minute, pass from the bottom of vent tank 16 through pipe 20, controlled by liquid level regulator 21, through heat exchangers 22 and 23 where the temperature is raised to about 260° F. by the input of 15,400,000 B. t. u., then through heater 24 wherein the temperature is further raised to 380° F. by the input of 4,780,000 B. t. u. to the upper part of stripper 19.

In stripper 19, absorption oil having a gravity of about 36 A. P. I. is withdrawn from the bottom at a temperature of about 375° F. and at the rate of about 218 gallons per minute through pipe 25, controlled by liquid level regulator 26, and passes in heat exchanging relationship with the oil fed to stripper 19 through exchangers 23 and 22 and thence to an absorption oil accumulator 27a for storage and reuse in the system.

Stripper 19 is held under about 55 pounds' gage pressure, steam being introduced at the rate of about 1600 pounds per hour through pipe 75 19a, and certain gaseous and vaporized hydro-

carbons pass from the top thereof at a temperature of about 380° F. through pipe 28 and heat exchanger 29 wherein an output of 4,786,000 B. t. u. is effected to reduce the temperature to about 150° F. The liquefied and gaseous fractions then pass through a cooler 30 wherein 5 1,000,000 B. t. u. are exchanged causing a further drop in temperature to about 75° F.

Any water is then removed in trap 31 and the mixture then comprising liquid hydrocarbons of about 53.6 A. P. I. gravity is discharged into the lower part of absorption tower 32.

The mixture is supplied to what is termed a low pressure absorption tower 32 at the rate of about 36 gallons per minute of the liquid together with gas at the rate of about 1,640,000 cubic feet per day.

Absorption tower 32 is operated under about 52 pounds' gage pressure and is supplied with absorption oil from accumulator 27a through 20 pipe 33, pump 34, flow regulator 35 and cooler 36 in which latter the temperature is reduced to about 75° F.

The absorption oil containing desired constituents and of a gravity of about 45.8 A. P. I. 25 passes from the bottom of tower 32 through pipe 27, controlled by liquid level regulator 38, at the rate of about 72 gallons per minute while at a temperature of about 90° F. and has the following constituents:

	Mol. %
C ₁	0.69
C ₂	2.32
C ₃	9.10
C ₄	3.22
C ₄	7.52
C ₅₊	21.05
Absorption oil	56.10

The stream is led through heat exchanger 29 by pump 39a wherein its temperature is raised 40 to about 340° F. and then through heater 38a to maintain such temperature.

It is clear that under certain conditions of length of pipe, insulation, etc. heater 38a may be dispensed with and the oil heated solely in 45 heat exchanger 29.

The oil, thus heated to about 340° F., is passed into fractionator 39 which operates under about 55 pounds' gage pressure to cleanly separate the absorption oil from the remaining 50 constituents and said absorption oil of about 36 gravity A. P. I. is withdrawn from the bottom of fractionator 39 through pipe 40, controlled by liquid level regulator 41, and flows at the rate of about 55 gallons per minute while at a temperature of about 330° F. back to pipe 25 leading from stripper 19 and the thus commingled streams flow at the rate of about 273 gallons per minute while at a temperature of about 366° F. through heat exchangers 23 and 22 to 60 accumulator 27a for reuse.

Fractionator 39 is supplied with about 650 pounds of steam per hour through pipe 42a and is equipped with a bottom heater 42, which may be the usual closed steam coil, and the gaseous 65 and vaporized constituents at a temperature of about 200° F. pass from the upper part thereof through pipe 43, and cooler 44 to a reflux condensate tank 45 at a temperature of about 75° F.

Any gaseous and vaporized hydrocarbons are 70 taken from the top of reflux tank 45 and passed through pipe 45a back to pipe 28 prior to the latter's discharge into absorber 32 so that there may be as complete a recovery as possible of desired constituents. Tower 32 thus functions 75

as both a primary low pressure absorber and a reabsorber.

Some of said reflux condensate at a temperature of about 75° F. is withdrawn through pipe 46 controlled by temperature controlled regulator 47 to act as reflux in fractionator 39 at about 17.5 gallons per minute, water being drawn off through trap 46a, while another portion at a temperature of about 75° F. is fed at the rate of about 16 gallons per minute through pipe 48 controlled by level regulator 49, and heat exchanger 50 at a temperature of about 190° F. to a stabilizer 51, water being drawn off through trap 48a.

The gravity of the reflux condensate is about 110.8 A. P. I. and comprises the following:

	Mol. %
C ₁	0.23
C ₂	2.97
C ₃	18.63
C ₄	7.41
C ₄	17.96
C ₅₊	52.70

The thus heated reflux condensate is treated in stabilizer 51 at about 200 pounds gage pressure, said stabilizer being equipped with a bottom heater 52, wherein undesired constituents are finally separated to pass out through pipe 53 at a temperature of about 135° F. to be cooled to about 75° F. in cooler 54 and received in reflux condensate tank 55.

A portion of this last-named reflux condensate is withdrawn through pipe 56 governed by flow regulator 57, and used as a reflux medium in stabilizer 51 at the rate of about 17.5 gallons per minute, while a second portion may be withdrawn, if desired, through level regulator 58.

The desired finished gasoline is passed at a temperature of about 270° F. through pipe 59, controlled by liquid level regulator 60, heat exchanger 50, and cooler 61 at a temperature of about 75° F. to a storage tank 62 at the rate of about 19,274 gallons per day, gravity about 100 A. P. I. consisting of:

C ₄	7.60 mol. %; 6.40 vol. %
C ₄	23.40 mol. %; 19.24 vol. %
C ₅₊	69.00 mol. %; 74.36 vol. %

Coming now to an important feature of the invention, undesired constituents consisting of:

	Mol. %
C ₁	1.0
C ₂	12.71
C ₃	79.55
C ₄	6.74

are taken from tank 55 through pipe 63 and back pressure regulator 64 to a header 65 into which is likewise led undesired constituents from absorber 32 through pipe 66 consisting of:

	Mol. %
C ₁	49.30
C ₂	24.15
C ₃	22.10
C ₄	2.17
C ₄	2.28

Such combined stream of constituents undesired in the final product is passed into the bottom of a so-called saturating absorber 67, supplied with absorbent oil from accumulator 27a by means of pipe 68, pump 69, flow regulator 70, and cooler 71 at the rate of about 242 gallons per minute, its temperature being reduced by cooler 71 from

about 125° F. to about 80° F. while the saturating absorber operates under a pressure of about 50 pounds gage.

In high pressure systems for treating natural gas, it is important to separate desired constituents and conserve all the gas. Therefore, the residue gases from pipe 65 are passed into saturating absorber 67 wherein about 50% of all such gases are absorbed, or practically everything but methane and ethane which may be withdrawn through pipe 72 at the rate of about 1,081,000 cubic feet per day in the following proportions:

	Mol. %
C ₁	71.50
C ₂	28.50

and may be used for fuel.

The remaining gas absorbed in the oil passes through pipe 73, controlled by level regulator 74, pump 75, and cooler 76, at a temperature of about 75° F. and at the rate of 254 gallons per minute, said oil being about a gravity of 39.6 A. P. I., to absorber 11.

The gravity of the oil from saturating absorber 67 will vary with the composition of the gas absorbed as well as with the temperature and pressure of the absorption step and, for commercial operations, will range from about 33 A. P. I. to 45 A. P. I., but the gravity will always be materially increased over the gravity of the hydrocarbon oil originally used for absorption as, for instance, coming from stripper 19 and fractionator 39.

As illustrative of the described process, the oil from absorber 67 has the following mol. percentages:

	Mol. %
C ₁	0.7
C ₂	2.14
C ₃	9.79
C ₄	0.81
C ₄	0.80
Absorption oil	85.76

which causes an increase in gravity of the absorption oil from 36 A. P. I. to 39.6 A. P. I.

The cycle of operations from absorber 11 has been described, but the function of saturating absorber 67 in the system is highly important because as the pressure is stepped up by pump 75, this pump can handle the absorption oil with its absorbed gases and eliminates the use of a recompressor.

By reason of this action the number of liquid mols entering and leaving absorber 11 are nearer the same than if absorbent oil alone was used and thus better absorption of finally desired constituents is obtained.

Again, the load on absorber 11 is materially reduced by the use of saturating absorber 67 because only constituents desired in the final product are picked up in absorber 11; hence the temperature rise through absorber 11 is greatly reduced, thus permitting a material reduction in the volume of absorption oil required as well as a reduction in the capacity of apparatus required.

The function of stripper 19 is to completely denude the absorption oil of all absorbed constituents by providing such pressure, temperature, and live steam as will cause the desired evaporation up to a point where some of the heavier absorption oil will be carried over.

The system is applicable to both high and low pressure gasoline recovery plants. When low

pressures of the order of 25 to 100 pounds are used in absorber 11, the stripper 19 may be bypassed and the rich absorption oil taken directly to fractionator 39 through suitable heat exchangers.

Likewise, liquid reflux from tank 55 may be taken to be introduced into saturating absorber 67 together with gaseous hydrocarbons to the same effect as described.

10 The plant, as described, has greater flexibility in producing finished gasoline at varying specifications over present known absorption plants, particularly when the recovery of pentane and heavier hydrocarbons in the gas together with varying percentages of butane is desired, practically all methane, ethane, and propane being eliminated.

15 The described system, in addition to flexibility, carries such heat load as to greatly reduce initial 20 investment costs as well as operating costs.

20 Due to its efficiency, the steam boiler capacity is greatly reduced as undesired constituents are largely eliminated before fractionation and therefore the fractionator and stabilizer can be of 25 minimum size. This reflects also on the coolers which, therefore, can be smaller due to lowered heat load.

25 As an illustration by comparative figures, the heat load for the above described system is about 30 8,481,000 B. t. u. per hour, steam 10,200 pounds per hour. A plant of equal capacity according to the present best known design will require about 11,000,000 to 12,000,000 B. t. u. per hour.

35 When it is known that on ordinary pipe line absorption systems steam costs about 25 cents per million B. t. u. per hour using natural gas for fuel, the differential in this respect alone in favor of the present invention is apparent, especially in this art where high economy in costs 40 is necessary to operate in a highly competitive industry.

45 It should be understood that where live steam has been used herein, it acts mainly by partial pressure effects to strip the liquids thoroughly and not particularly as a heat transfer agent. Being chemically inert as to the hydrocarbons, it is possible at times to replace the steam with other inert gases for stripping purposes such as nitrogen, carbon dioxide and the like, but such is not 50 generally desirable due to the lower specific heat of such other inert gases.

55 As applied herein, the mol. per cent means the relative number of molecules of each constituent, or group of constituents, present in a hydrocarbon mixture whether in the liquid or vapor phase. For instance, a 36° A. P. I. oil of 200 mol. weight designates an oil having 0.0352 mol. per gallon or one in which 13.4 standard cubic feet of vapor would condense to form one gallon of liquid. This designation is particularly adapted to the absorption oil of 36° A. P. I. gravity referred to herein which has a mean molecular weight of about 200.

I claim as my invention:

1. A process of treating natural gas which comprises: flowing a stream of natural gas containing hydrocarbons of the methane series, such as pentane and lighter and pentane and heavier, through absorption oil under such conditions of 70 temperature and pressure that the greater part of the hydrocarbons lighter than butane are unabsorbed, removing such unabsorbed hydrocarbons from the system, decreasing the pressure and increasing the temperature on said absorption oil to completely remove all absorbed hydro-

carbons, condensing and stabilizing said removed hydrocarbons to recover a liquid fraction containing some iso-butane and a relatively large percentage of hydrocarbons heavier than iso-butane also a gaseous fraction containing some iso-butane and a relatively large percentage of hydrocarbons lighter than iso-butane, passing said gaseous fraction through absorption oil under lower pressure conditions than said first-mentioned absorption oil to absorb substantially all propane and heavier hydrocarbons while methane and ethane are substantially unabsorbed, then stepping up the pressure on said last absorption oil to contact said original stream of gas and complete the cycle.

2. A process of treating natural gas which comprises: flowing a stream of natural gas containing hydrocarbons of the methane series, such as pentane and lighter and pentane and heavier, through absorption oil under such conditions of 20 temperature and pressure that the greater part of the hydrocarbons lighter than butane are unabsorbed, removing such unabsorbed hydrocarbons from the system, decreasing the pressure and increasing the temperature on said absorption oil to completely remove all absorbed hydrocarbons by steps including fractionation, condensing the heavier portion of said fractionated hydrocarbons and stabilizing same to recover a liquid fraction containing some iso-butane and 30 a relatively large percentage of hydrocarbons heavier than iso-butane also a gaseous fraction containing some iso-butane and a relatively large percentage of hydrocarbons lighter than iso-butane, passing said gaseous fraction through absorption oil under lower pressure conditions than said first-mentioned absorption oil to absorb substantially all propane and heavier hydrocarbons while methane and ethane are substantially unabsorbed, then stepping up the pressure on said 35 last absorption oil to contact said original stream of gas and complete the cycle.

3. A process of treating natural gas which comprises: flowing a stream of natural gas containing hydrocarbons of the methane series, such as 45 pentane and lighter and pentane and heavier, through absorption oil under such conditions of temperature and pressure that the greater part of the hydrocarbons lighter than butane are unabsorbed, removing such unabsorbed hydrocarbons from the system, decreasing the pressure and increasing the temperature on said absorption oil to completely remove all absorbed hydrocarbons and stripping the same with an inert gas, cooling said stripped hydrocarbons and condensing part thereof, passing the vaporized part of the cooled hydrocarbons through further absorption oil to reabsorb a liquid fraction and separate out a gaseous fraction, passing said absorption oil containing said reabsorbed liquid fraction 55 first in heat exchange relation with said stripped hydrocarbons to cool such hydrocarbons then into a fractionator to completely remove all reabsorbed hydrocarbons, stabilizing said removed hydrocarbons to recover a liquid fraction containing some iso-butane and a relatively large percentage of hydrocarbons heavier than iso-butane also a gaseous fraction containing some iso-butane and a relatively large percentage of hydrocarbons lighter than iso-butane, passing said 60 gaseous fraction through absorption oil under lower pressure conditions than said first-mentioned absorption oil to absorb substantially all propane and heavier hydrocarbons while methane and ethane are substantially unabsorbed, then 65

stepping up the pressure on said last absorption oil to contact said original stream of gas and complete the cycle.

4. A process of treating natural gas which comprises: flowing a stream of natural gas containing hydrocarbons of the methane series, such as pentane and lighter and pentane and heavier, through absorption oil under such conditions of temperature and pressure that the greater part 5 of the hydrocarbons lighter than butane are unabsorbed, removing such unabsorbed hydrocarbons from the system, decreasing the pressure and increasing the temperature on said absorption oil to completely remove all absorbed hydrocarbons and stripping the same with an inert gas, cooling said stripped hydrocarbons and condensing part thereof, passing the vaporized part of the cooled hydrocarbons through further absorption oil to reabsorb a liquid fraction and separate 10 20 out a gaseous fraction, passing said absorption oil containing said reabsorbed liquid fraction first in heat exchange relation with said stripped hydrocarbons to cool such hydrocarbons then into a fractionator to completely remove all reabsorbed hydrocarbons, stabilizing said removed hydrocarbons to recover a liquid fraction containing some iso-butane and a relatively large percentage of hydrocarbons heavier than iso-butane also a gaseous fraction containing some iso-butane and a relatively large percentage of hydrocarbons lighter than iso-butane, passing said gaseous fraction together with the gaseous fraction separated from said reabsorption oil through absorption oil under lower pressure conditions than 25 30 said first-mentioned absorption oil to absorb substantially all propane and heavier hydrocarbons while methane and ethane are substantially unabsorbed, then stepping up the pressure on said last absorption oil to contact said original stream 35 40 of gas and complete the cycle.

5. In a process for recovering casing-head gasoline from natural gas containing hydrocarbons of the methane series including butane and lighter hydrocarbons in which the gas is contacted with absorption oil under such conditions of temperature and pressure that propane and heavier hydrocarbons are absorbed but the major portion of the gas remains unabsorbed, the enriched absorption oil is then treated to completely remove all 45 50 absorbed hydrocarbons and to recover a liquid fraction and a gaseous fraction from said removed hydrocarbons, that combination of steps which comprises: passing said gaseous fraction as a gas through absorption oil under conditions of temperature and pressure that propane and heavier hydrocarbons are absorbed therein while methane and ethane are but slightly absorbed, then stepping up the pressure on such oil last mentioned and contacting the same with said original gas.

6. In a process for recovering casing-head gasoline from natural gas containing hydrocarbons of the methane series including butane and lighter hydrocarbons in which the gas is contacted with absorption oil under such conditions of temperature and pressure that propane and heavier hydrocarbons are absorbed but the major portion of

the gas remains unabsorbed, and the absorption oil is then treated to recover a liquid fraction therefrom including propane and heavier hydrocarbons, that combination of steps which comprises: raising the temperature and decreasing the pressure on said contacted absorption oil to completely remove all absorbed hydrocarbons, cooling said removed hydrocarbons and liquefying a portion thereof, reabsorbing said removed hydrocarbons in further absorption oil to absorb 10 at least a portion of the propane and heavier hydrocarbons therein, passing said reabsorbed hydrocarbons in heat exchange relationship with said removed hydrocarbons, separating the reabsorbed hydrocarbons from said further absorption oil then stabilizing said separated hydrocarbons. 15

7. In a process for recovering casing-head gasoline from natural gas containing hydrocarbons of the methane series including butane and lighter hydrocarbons in which the gas is contacted with absorption oil under such conditions of temperature and pressure that propane and heavier hydrocarbons are absorbed but the major portion of the gas remains unabsorbed, and the absorption oil is then treated to recover a liquid 20 fraction therefrom including propane and heavier hydrocarbons, that combination of steps which comprises: raising the temperature and decreasing the pressure on said contacted absorption oil to completely remove all absorbed hydrocarbons, 25 cooling said removed hydrocarbons and liquefying a portion thereof, reabsorbing from the uncondensed vapors the desirable hydrocarbons in further absorption oil to absorb at least a portion of the propane and heavier hydrocarbons therein, 30 passing said reabsorbed hydrocarbons in heat exchange relationship with said removed hydrocarbons, then fractionating said further absorption oil to separate said propane and heavier hydrocarbons and stabilizing said separated hydro- 35 carbons. 40

8. In a process for recovering casing-head gasoline from natural gas containing hydrocarbons of the methane series including butane and lighter hydrocarbons in which the gas is contacted with absorption oil under such conditions of temperature and pressure that propane and heavier hydrocarbons are absorbed but the major portion of the gas remains unabsorbed, the pressure on the absorption oil is decreased while its temperature is increased to completely remove all absorbed hydrocarbons, said removed hydrocarbons are cooled and reabsorbed in further absorption oil to separate out an undesired gaseous fraction 45 the major portion of which consists of propane and lighter hydrocarbons, that combination of steps which comprises: passing said gaseous fraction through absorption oil under such conditions of temperature and pressure that substantially all propane and heavier hydrocarbons are absorbed therein while methane and ethane are substantially unabsorbed, then stepping up the pressure on said absorption oil and contained gases 50 and contacting the same with said original gas. 55 60

ARTHUR JOHN LINDSAY HUTCHINSON.
